UNITED STATES PATENT OFFICE.

ZACHARY EARL RUSSELL, OF SAUK RAPIDS, MINNESOTA.

ADVERTISING-CARD HOLDER.

Application filed July 18, 1921. Serial No. 485,544.

To all whom it may concern:

Be it known that I, ZACHARY EARL RUSSELL, a citizen of the United States, residing at Sauk Rapids, in the county of Benton and State of Minnesota, have invented certain new and useful Improvements in Advertising-Card Holders; and I do hereby declare the following to be a full, clear, and exact description of the invention, such as 10 will enable others skilled in the art to which it appertains to make and use the same.

This invention relates to an advertising device, and particularly, to such a device adapted to be attached to an automobile or 15 other vehicle. It has become quite a common practice to attach signs of various kinds to automobiles, so that when the machine is driven about the city, the sign will be exhibited.

20 It is an object of this invention to provide a simple and inexpensive device adapted to receive an advertising card and which may be quickly and easily attached to an automobile without providing such automobile 25 with any additional fastening mechanism.

It is a further object of the invention to construct such a device of flexible material and to provide the same with fasteners adapted to engage the usual curtain buttons 30 of the automobile.

These and other objects and advantages of the invention will be fully apparent from the following description made in connection with the accompanying drawings in 35 which like reference characters refer to the same parts throughout the different views, and in which—

Fig.1 is a plan view of the device showing an advertising card therein;

40 Fig. 2 is a vertical section taken on the line 2—2 of Fig. 1;

Fig. 3 is a similar section showing the parts on an enlarged scale; and Fig. 4 is a horizontal section taken on line 4—4 of 45 Fig. 1.

Referring to the drawings, the device is seen to comprise a rear or backing portion 1 of solid material and a front or border portion 2. The border portion 2 surrounds an 50 opening of general rectangular form and a flexible sheet of transparent material 3, such as celluloid, is secured to said border portion. A piece of material 4 is folded over the top edge of the border portion 2 and 55 forms a reinforcing means therefor, the rear edge of said piece of material extending

downwardly over the backing portion 1. The border portion 2 is stitched with a double row of stitching around the bottom and sides of the device, which stitching extends through the backing portion 1. The upper edge however of the backing portion is free, thus forming an open side through which the advertising card *a* may be inserted. The inner row of stitching through the border portion also passes through the sheet 3 and secures the same in position. Two rows of stitching are also passed through the top portion of the device above the top edge of the backing 1. These rows 70 of stitching pass through the folded over portion 2 and the piece of material 4.

In actual construction, the device is made of but two pieces of fabric. One of these pieces is of substantially rectangular form 75 but somewhat wider at one end, the wider end having a rectangular opening cut therein. The piece is first folded so that the narrower and solid portion substantially covers the rectangular opening in the wider 80 portion. The edges of the wider portion are then folded inwardly at the outer side, as shown at 2^a, to be of the same width as the solid portion which forms the backing portion 1. The edge of the piece above the 85 rectangular opening is now folded rearwardly forming the piece 2^b, which extends downwardly below the upper edge of the portion 1. The second piece of material which is also of general rectangular shape, 90 shown as 4, is now folded over the top of the device, the sheet of transparent material 3 inserted, as shown, and the rows of stitching, then added to secure the portions together, thus forming a flexible open 95 envelope.

The device is adapted to be secured to the buttons customarily provided on the automobile top for the side curtains, and to this end the device is provided at each end with 100 spaced fastener members 5 which are of open resilient construction adapted to be positioned over the said curtain buttons. The device can thus be quickly and easily attached and detached from the vehicle 105 without any change in the latter. The rear edge of the piece 4 covers the opening of the device so that dust and dirt is effectively prevented from entering the same. The surface of the advertising card is also protected 110 by the transparent sheet 3 and yet said card is clearly visible and readable therethrough.

While any desired material may be used, it has been found, in practice, that the material commonly used for vehicle or automobile curtains is very efficient for the purpose. The device can, of course, be made of different sizes, either to extend along the side of the automobile or to extend entirely across the back thereof. The device being made of flexible material, it is in no danger of being broken, can be readily applied and withstands the shocks incident to the motion of the vehicle without any damage or deterioration.

It will, of course, be understood that various changes may be made in the form, details and proportions of the device without departing from the scope of applicant's invention, which, generally stated, consists in the matter shown and described and set forth in the appended claims.

What is claimed is:—

1. An advertising card exhibiting device comprising a substantially rectangular flexible backing portion, a border portion of flexible material overlying said backing portion around the edges thereof and secured thereto, except at the top edge, thus forming therewith a card retaining recess, a transparent sheet of flexible material inside of said border, and means at each end of the device extending through the border and backing portion for attaching the same to the curtain buttons of an automobile.

2. An advertising device comprising a flat flexible envelope adapted to receive an advertising card having a flexible transparent sheet of material in the front thereof, through which said sign is visible, said envelope being open at its top edge and having a piece of material folded over the top edge and secured at each side thereof forming a reinforcing strip and extending downwardly at the rear portion over the opening

of the envelope, and spaced means at each end of the envelope extending therethrough for securing the same to the curtain buttons of a vehicle.

3. An advertising device comprising a flexible envelope of general rectangular form adapted to receive an advertising card having a flexible transparent face, and means at each end thereof for securing the same to the curtain holding means of an automobile.

4. An advertising device consisting of a piece of material of general rectangular shape but wider at one end than the other and having a rectangular opening cut in said wider end, said piece being folded along a substantially central line to bring the solid portion over the said opening and then having the wider portion folded inwardly under the folded-over portion, a piece of flexible transparent material placed beneath the folded portions and stitched along the bottom and sides, the top edge of the folded-over solid portion being left free whereby an open-sided flexible envelope is formed having a transparent flexible face.

5. The structure set forth in claim 4, the top edge of the wider portion of the piece of material being also folded rearwardly to extend beyond and beneath the folded-over edge of the narrower portion.

6. The structure set forth in claim 4, and an extra piece of material folded over the top edge and stitched thereto, the rear edge of this piece of material also extending beyond and overlapping the free edge of the folded narrower piece of material.

In testimony whereof I affix my signature in presence of two witnesses.

ZACHARY EARL RUSSELL.
